UNITED STATES PATENT OFFICE.

PERCY R. SAUNDERS, OF ANTIGONISH, NOVA SCOTIA, CANADA.

HEAD-REST.

1,275,607.

Specification of Letters Patent. Patented Aug. 13, 1918.

Application filed April 18, 1918. Serial No. 229,238.

To all whom it may concern:

Be it known that I, PERCY R. SAUNDERS, a subject of the King of Great Britain, residing at Antigonish, in the Province of

5 Nova Scotia, Dominion of Canada, have invented a new and useful Head-Rest; and I do hereby declare the following to be a full, clear, and exact description of the invention, such as will enable others skilled in the art 10 to which it appertains to make and use the same.

The present invention relates to a head rest attachment for bedsteads, and has for its object to provide a device of this character 15 which embodies novel features of construction whereby a back and head rest of any desired inclination can be easily and quickly provided.

Further objects of the invention are to 20 provide a head rest which is simple and inexpensive in its construction, which can be readily applied as an attachment to an ordinary bedstead, which can be quickly adjusted and locked at any desired angle or inclination, and which enables the same results to 25 be accomplished with a single pillow which usually require the use of several pillows.

With these and other objects in view, the invention consists in certain novel combinations and arrangements of the parts as will 30 more fully appear as the description proceeds, the novel features thereof being pointed out in the appended claims.

For a full understanding of the invention, 35 reference is to be had to the following description and accompanying drawings, in which:—

Figure 1 is a perspective view of a head rest constructed in accordance with the invention, showing it applied to the head of an ordinary bedstead.

Fig. 2 is a detached perspective view of the head rest.

Corresponding and like parts are referred 45 to in the following description and indicated in all the views of the drawings by the same reference characters.

Referring to the drawings, which illustrate one possible embodiment of the invention, the reference character A designates the head of an ordinary bedstead, the frame thereof including the usual upper and lower horizontal bars 1. The head rest includes an upright supporting frame B which is rigidly 50 clamped in position upon the head of the bedstead and an inclined frame C which is

adjustably connected at one end to the upright frame B and adapted to support a pillow D at any desired inclination. The upright frame B may be formed of any suitable 60 material and be of any desired shape. As illustrated upon the drawing it has a rectangular formation and includes vertical side bars 2, an upper cross bar 3, and a lower cross bar 4. The upper cross bar 3 is offset 65 rearwardly at 3^a, and provided with a pair of slots 5 which loosely receive the stems of clamping hooks 6, said stems being threaded and having thumb nuts 7 mounted thereon. The middle portion 4^a of the lower cross bar 70 4 is also offset rearwardly, the offset arms including downwardly opening crimped portions 4^b and straight portions 4^c. These crimped portions 4^b form downwardly opening hooks which can be fitted over the lower 75 cross bar 1 of the head A, while the straight portions 4^c in connection with the sides of the crimps 4^b provide upwardly facing hook members which are adapted to engage the lower cross bar 1 of the head A, as indicated 80 on Fig. 1. With the arrangement indicated by Fig. 1 the clamping hooks 6 extend upwardly from the supporting frame and engage the upper cross bar 1 of the head A, although with a differently designed bed- 85 stead it might be more convenient to reverse the position of the clamping hooks 6 and engage the lower cross bar 1 of the head A with the crimped portions 4^b of the offset arms at the bottom of the frame. In either in- 90 stance the upright frame can be rigidly secured to the head A of the bedstead without difficulty.

A cross bar 8 extends transversely across the upright frame B, being provided at the 95 ends thereof with guides 9 which are slidable upon the vertical sides of the upright frame. Clamping screws 10 enable this cross bar 8 to be clamped rigidly in any desired position. The inclined pillow supporting frame 100 C is shown as having a U-shaped formation, the ends thereof being pivotally connected to the cross bar 8. As shown upon the drawing the ends of the frame terminate in eyes 11 which pivotally engage the cross bar. A pillow clamping bar 12 is mounted upon the cross bar 8, the ends of the pillow clamping bar being extended downwardly at 12^a, and one end being pivotally connected at 13 to the cross bar, while the other end is hooked 110 at 14 so as to detachably engage the cross bar. A strip of fabric 15 or the like is stretched

across and suitably secured to the adjustable pillow supporting frame C. The pillow D is placed upon this support and the clamping bar 12 caused to engage an intermediate portion of the pillow, the portion of the pillow above the clamping bar being returned forwardly to provide a head rest, as indicated by Fig. 1. The same results which ordinarily require the use of several pillows can thus be 5 accomplished with a single pillow, and the frame C can be quickly adjusted and set at any desired inclination, or moved upwardly into an out of the way position when not in use.

10 15 Having thus described the invention, what I claim as new and desire to secure by Letters Patent, is:—

1. A head rest attachment for bedsteads, including an upright frame, means for 20 rigidly securing the frame to the head of a bedstead, a cross bar adjustably mounted upon the upright frame, and an inclined pillow supporting frame pivotally connected at its upper end to the cross bar.

25 2. A head rest attachment for bedsteads, including an upright frame, means for rigidly securing the upright frame to the head of a bedstead, a cross bar adjustably mounted upon the upright frame, an inclined 30 pillow supporting frame pivotally connected at its upper end to the cross bar, and a transversely extending pillow clamping bar at the upper end of the inclined frame.

35 3. A head rest attachment for bedsteads, including an upright frame, means for rigidly securing the frame to the head of a bedstead, a cross bar adjustably mounted upon the upright frame, an inclined pillow 40 supporting frame pivotally connected at its upper end to the cross bar, and a transverse pillow clamping bar having the extremities thereof bent laterally, one of the laterally bent ends being pivotally connected to the 45 cross bar, while the other end is provided with latch means for detachably engaging the cross bar.

4. A head rest attachment for bedsteads, including an upright frame, means for 50 rigidly securing the frame to the head of a bedstead, a cross bar adjustably mounted upon the upright frame, a U-shaped pillow supporting frame having the ends of the arms thereof pivotally connected to the cross 55 bar, fabric stretched across the U-shaped

frame, and a transverse pillow clamping bar having the extremities thereof bent laterally, one of the said laterally bent ends being pivotally connected to the cross bar, while the other end is provided with latch means 60 for detachably engaging the cross bar.

5. A head rest attachment for bedsteads, including an upright frame provided at one end with hooked portions, clamping hooks at the opposite end of the frame for coöperation with the said hooked portions to rigidly secure the frame to the head of a bedstead, a cross bar adjustable upon the upright frame, and an inclined pillow supporting frame pivotally connected at one end to the 70 cross bar.

6. A head rest attachment for bedsteads, including an upright frame having one end thereof provided with oppositely facing hooked portions, while the other end is provided with reversible clamping hooks adapted to be positioned for coöperation with one of the said hooked portions to engage the head of the bedstead and rigidly secure the frame in position, a cross bar adjustable 75 upon the upright frame, an inclined pillow supporting frame pivotally connected at one end to the cross bar.

7. A head rest attachment for bedsteads, including an upright rectangular frame, one 80 end of which is offset rearwardly and provided with openings, while the other end has a portion thereof correspondingly offset laterally and provided with offset arms having straight portions and crimped portions 85 which provide oppositely facing hook members, reversible clamping hooks having the stems thereof passed loosely through the openings of the first mentioned offset end, said clamping hooks being adapted to coöperate with either of the before mentioned hook members to engage the head of the bedstead, clamping nuts threaded on the stems of the clamping screws; a cross bar adjustable upon the upright frame, and an inclined 90 pillow supporting frame pivotally connected to the cross bar.

In testimony whereof I have signed my name to this specification in the presence of two subscribing witnesses.

PERCY R. SAUNDERS.
